L. P. TEED.

Combined Thrashing Machine and Grain Separator.

No. 78,843.

Patented June 9, 1868.

Fig. 1

United States Patent Office.

LORENZO P. TEED, OF LEWISBURG, PENNSYLVANIA.

Letters Patent No. 78,843, dated June 9, 1868.

IMPROVEMENT IN COMBINED THRESHING-MACHINE AND GRAIN-SEPARATOR.

The Schedule referred to in these Letters Patent and making part of the same.

TO ALL WHOM IT MAY CONCERN:

Be it known that I, LORENZO P. TEED, of Lewisburg, Union county, Pennsylvania, have invented a combined Threshing-Machine and Grain-Separator; and I do hereby declare the following to be a full, clear, and exact description of the same.

My invention consists of the combination of certain grain-cleaning and separating devices, fully described hereafter, with ordinary threshing-mechanism, the whole forming a compact and efficient machine, the various parts of which can be operated from a single driving-shaft.

In order to enable others skilled in the art to make and apply my invention, I will now proceed to describe its construction and operation, reference being had to the accompanying drawing, which forms a part of this specification, and in which—

Figure 1 is a sectional elevation of my combined threshing-machine and grain-separator.

Figure 2, a plan view of the same, partly in section.

Figure 3, a transverse sectional view, on the line 1 2, fig. 1.

Figure 4, a sectional elevation of a portion of the machine.

Figure 5, a plan view of fig. 4, and

Figures 6, 7, 8, and 9 detached views, drawn to an enlarged scale, and illustrating portions of my invention.

Similar letters refer to similar parts throughout the several views.

The two side frames A and A' of the machine are braced by horizontal bars and uprights, a, and are connected together by cross-pieces, a².

The threshing-mechanism, at the front portion of the machine, is similar to that in common use.

Power may be applied to the threshing-cylinder, B, from an adjoining horse-power or portable engine, either by a belt passing around a pulley, b¹, at one end of the shaft b, or by a rotating rod or shaft, X, shown in red lines, fig. 4. In the latter case the rod X is coupled to one end of a spindle, d, which turns in suitable bearings in the cross-pieces a¹ and a², and is terminated at its inner end by a bevel-wheel, d¹, gearing into a similar wheel at the inner end of a spindle, e, the latter having, at its opposite end, a cog-wheel, e', which gears into a pinion, e'', of the shaft b, (see figs. 4 and 5.)

The inner end of the spindle e turns in a stationary bearing, f, and its outer end in a block, f¹, hinged to one of the uprights, a, of the machine, the said block being raised or lowered by a lever, c, with which it is connected by a link, f². The cog-wheel e' is by this means thrown in or out of gear with the pinion e'', as will be more fully described hereafter.

At the rear of the usual platform, c, of the threshing-machine, and on line with the same, is a shaker-frame, D, which is hung to the opposite side frames A and A' of the machine by vibrating arms, g, in an inclined position, its rear end being the most elevated.

The bottom of the frame D is composed of a number of slats, g¹ and g², a space intervening between each of the latter for the passage of grain, as hereafter described, and a longitudinal reciprocating motion is imparted to the said frame by rods, h, secured to its under side, and connected to a double crank-shaft, E.

The latter projects through and turns in the opposite side frames A and A', one end being terminated by a fly-wheel, h¹, of a suitable diameter, and the opposite end by a pulley, h², fig. 3, connected by a belt to a pulley, h³, of the driving-shaft b.

Directly over the slats g¹ of the shaker-frame is an apron, F, composed of a number of strips of sheet metal, placed side by side, and arranged to vibrate freely and independently upon a rod, i, secured to the opposite side frames, (see figs. 1 and 3.)

A fan-spindle, G, turns in suitable bearings, secured to the side frames A and A', and in each of the latter is the usual opening, j, for the admission of air to the fan G', which turns in a curved box, k, there being at the rear of the latter the usual grain-receptacles, j¹ and j².

Over one or both of the openings j of the fan-box is secured a plate, I, figs. 6 and 7, over an opening in

which are hung three or more slats, k^1 , opening outwards, and connected together by a rod, k^2 , the latter being acted upon by a spiral spring, k^3 , in such a manner as to slightly elevate the slats, and allow the passage of air between them into the box, as shown in fig. 6, and all of which will be more fully described hereafter.

The fan-spindle G is turned by means of a pulley, l , at one end of the same, connected by a belt to a pulley, l^1 , of the driving-shaft b , and at the opposite end of the fan-spindle is a grooved pulley, m , which communicates motion, by means of a cord or belt, to a spindle, n , fig. 1, which turns in the opposite side frames of the machine at a point above and at the rear of the fan-box k . This spindle, at a point about midway between the side frames, is provided with a band-wheel, p , connected by an endless band, q , to a similar wheel, p^1 , of a spindle, n^1 , which also turns in the opposite side frames.

The endless band q passes over and is almost in contact with the upper surface of a stationary platform, H , which is secured to the frame of the machine between the pulleys p and p^1 , and has an inclination somewhat greater than that of the shaker-frame D . To the endless band q , and at equal distances apart, are secured transverse bars, r^1 , for a purpose described hereafter.

A sieve-frame, J , provided with sieves, t and t^1 , is hung to the upper portion of the fan-box by a pin, s , and rods s^1 , figs. 1 and 2, in such a position as to be directly over the grain-receptacles j^1 and j^2 , and beneath the inner end of the platform H .

The sieve t of the sieve-frame is shown enlarged in figs. 8 and 9, and consists of a number of transverse movable slats, y , each armed with a number of wires, y^1 , pointing rearwards, the said slats being connected together, beneath the sieve, by a rod, y^2 , which slides in projections at the under side of the frame, and may be secured in any position to which it is adjusted by set-screws, fig. 8. This rod, when moved toward the rear of the machine, raises the upper edges of the slats, and separates them to a greater or less extent, so as to suit the size of the grain that is to pass between them.

A lateral vibrating motion upon the pin s is imparted to the sieve-frame by the usual bell-crank lever, n^2 , hung to the side frame A' , and connected to the sieve-frame by a rod, u^1 , and to a crank-pin on the pulley l by a rod u^2 , (see fig. 2).

At the rear of the sieve-frame is a platform, K , secured to the side frames of the machine at a somewhat greater inclination than the platform H , and at the opposite ends of this platform are spindles, v and v^1 , which turn in bearings secured to the platform, and which are provided with band-wheels, w , connected by an endless band, w^1 , the latter being almost in contact with the upper surface of the platform, and having transverse bars or scrapers, w^2 , secured to it at equal distances apart, figs. 1 and 2.

The spindle v is provided with supplementary pulleys, r , fig. 2, and at its outer projecting end with a grooved pulley, x , the latter being connected by a curved belt or cord to a smaller grooved pulley, x^1 , placed between the driving-pulley b^1 and pulley l^1 of the driving-shaft.

Operation.

Machines of this class are generally mounted upon wheels for convenience in shifting them about a barn-floor or other place in which they are used. The wheels, however, have generally been placed at opposite ends of the machine, rendering it difficult to turn the latter without raising one end—an objection which I obviate by placing the wheels, z , close together, and directly under the centre of weight, putting blocks beneath the opposite ends of the machine when in use, to prevent it from tilting.

If power be applied to the machine by the rod X , fig. 4, the lever C is raised until the cog-wheel e^1 is in gear with the pinion e^2 of the driving-shaft, the lever being held in its raised position by a hook, y . If, however, the power is applied to the driving-shaft by means of a belt on its pulley b^1 , the lever C is depressed until the cog-wheels e' and e'' are thrown out of gear with each other, as shown in dotted lines, fig. 4.

The threshing-cylinder B turns in the direction of its arrow, and motion is communicated from the driving-shaft by the gearing described to the various parts of the machine which turn in the direction of their arrows, fig. 1.

The grain is threshed from the ears in the usual manner in the threshing-machine, and is, together with the straw and chaff, discharged on to the shaker-frame D , the slats of which are of such a shape as to permit the threshed material to pass over them in a rearward direction only. The threshed material passes beneath the apron F , the plates of which turn upon their rod i , and adapt themselves to the quantity of the material passing beneath them.

This apron F serves the twofold purpose of preventing the return of loose pieces of straw without interfering with the free passage of the straw rearward, and, together with the top piece v , acts as a shield or guard for stopping grains that are violently discharged by the threshing-cylinder, and which would otherwise prove a serious annoyance to the attendants.

The threshed material passes over the shaker-frame, from the rear end of which the straw is removed, the grain and chaff falling through the interstices between the slats on to the platform H . From the latter it is scraped and carried downwards by the transverse bars or scrapers r^1 of the endless band q , and discharged on to the inner end of the sieve t of the vibrating-frame J .

The grain, owing to the peculiar shape and inclination of the slats which form the sieve, travels rearward over the same, dropping between the slats on to the sieve t^1 , the light chaff being, in the mean time, separated from the grain by a current of air from the rotating fan G' , and thrown on to the platform K , up and over which it is carried by the scrapers w^2 of the endless band w^1 .

The small and imperfect grains that fall upon the sieve t^1 pass through the interstices of the same and fall into the receptacle j^1 , the sound grain passing over the sieve and falling into the adjoining receptacle j^2 .

In some cases, especially if the fan G' be turned at a high rate of speed, the current of air might be strong

enough to throw not only the chaff but a portion of the grain on to the platform K. This I obviate by means of the plates I and their slats k^1 , the latter remaining open by the action of their spring, k^3 , as long as the fan is rotated at a moderate speed, but closing partly, owing to a partial vacuum produced within, the moment the speed of the fan is increased.

By this arrangement, which is entirely self-regulating, the supply of air to the fan is increased or diminished as required, so as to produce an even and proper current through the sieve-frame J. The slatted plates I also prevent loose pieces of straw from being drawn into the fan-box.

By thus combining the cleaning and separating-devices with the threshing-mechanism, a compact and efficient machine is obtained, the various parts of which are operated from a single driving-shaft, and, although I prefer, in new machines, to arrange the whole within a single frame, as above described, it will be evident that the rear portion of the machine may be made separately, the threshing-machine resting upon the projecting ends of the lower rails of the side frames A A', so that the thresher may be detached and the machines may be used separately when required.

If the machine be operated by the rod X, the lever C may be depressed, and the horse-power or engine instantly stopped, the various parts of the machine being permitted to continue moving by their own momentum in order to clear themselves of straw and chaff, and if the machine is operated by a belt, it may be thrown off at any time for the same purpose.

I claim as my invention, and desire to secure by Letters Patent—

1. The apron F, consisting of a number of sheet-metal strips, suspended above the shaker-frame D, substantially in the manner and for the purpose herein set forth.
2. The slats y , having wires y^1 at their edges and adjustable upon a frame, substantially as and for the purpose described.
3. A plate or plates, k^1 , so hung, adjacent to an opening in the case of a fan, G', that the passage of air into the said case will cause the plate to be adjusted, substantially as and for the purpose described.
4. The arrangement of the shaker-frame D, platforms H and K, bands g and w^1 , with their bars or scrapers, and the sieves t t^1 , all substantially as and for the purpose specified.

In testimony whereof, I have signed my name to this specification in the presence of two subscribing witnesses.

L. P. TEED.
